DOFFING BRUSH CYLINDER

Joseph W. Behle, Dallas, Tex., assignor to The Murray Company, Dallas, Tex., a corporation of Texas

Application August 9, 1937, Serial No. 158,109

11 Claims. (Cl. 19—60)

This invention relates to new and useful improvements in doffing brush cylinders.

One object of the invention is to provide an improved doffing brush cylinder which is particularly adapted for use in cleaners, extractors, and other cotton machines for removing cotton from the saw cylinders of such machines.

An important object of the invention is to provide an improved brush cylinder wherein metallic heads or supporting members are formed with peripheral recesses to receive the brush bars, together with improved arcuate retaining elements for holding said bars in place, said elements also acting to form the surface of the cylinder, whereby a hollow cylinder having a substantially continuous surface is had.

Another object of the invention is to provide an improved cylinder of the character described, wherein the recesses in each supporting head which receive the brush bars have extended flanges surrounding said recesses and disposed at right angles to the face of the head, whereby said flanges frictionally engage the bars to aid in holding said bars in position within the recesses; said flanges being either an integral part of the head or being attached thereto in a suitable manner.

A further object of the invention is to provide an improved doffing brush cylinder which is so constructed that its parts may be stamped, which eliminates casting and machining operations, whereby more accurate manufacture at reduced costs, is made possible.

A construction designed to carry out the invention will be hereinafter described, together with other features of the invention.

The invention will be more readily understood from a reading of the following specification and by reference to the accompanying drawing, in which an example of the invention is shown, and wherein:

Figure 1 is a view, partly in section and partly in elevation of a doffing brush cylinder, constructed in accordance with the invention.

Figure 2 is a transverse, sectional view, taken on the line 2—2 of Figure 1.

Figure 3 is a partial perspective view of one of the heads, and

Figure 4 is an enlarged, sectional detail, taken through one of the recesses in the head.

In the drawing, the numeral 10 designates a metallic end head or plate which is circular in shape and which is formed with an inwardly directed annular flange 11 at its periphery. Two of these heads are provided, one for each end of the

assembly and each head has a central opening 12 therein. A supporting shaft 13 extends through the opening 12 of the heads and is secured to said head by means of bearing collars 14. Each collar surrounds the shaft adjacent the inner side of one of the heads and is fixed on said shaft by means of set screws 15. An outwardly directed flange 16 on the collar engages the inner surface of the head and is riveted or otherwise secured thereto. Since the heads 10 form the ends of the cylinder assembly, they are of course, spaced from each other on the shaft.

A plurality of intermediate flanged heads 10' which are constructed in the same manner as the end heads 10, are mounted on the shaft 13 at spaced intervals between the end heads 10. These intermediate heads have central openings 12 through which the shaft extends but said intermediate heads are not secured to the shaft, being merely rotatable thereon and held in their spaced position as will be hereinafter explained. The end heads 10 and the intermediate heads 10' support longitudinal brush bars 17 which extend longitudinally of the cylinder and which have the usual outwardly projecting bristles 18 suitably mounted therein. Any desired number of brush bars may be provided around the circular heads and since the bars are mounted within each head in exactly the same manner, it is believed that a description of one head will suffice.

Each head is formed with a plurality of radial recesses 19 in its peripheral portion and each recess is substantially square so as to receive one of the brush bars 17, which is also substantially square in cross-section. However, it is pointed out that the size and shape of both recess and bar are subject to variation. The peripheral flange 11 of the head is of course, cut away above each recess to permit insertion of the bar (Figures 2 and 3). Each recess is reduced at its lower end as shown at 19' and this reduced portion is equal to the width of the bar 17 so that said bar has a tight fit therein. A flange 20 extends laterally from the bottom of the recess and when the bar is in position, it rests on this flange as is clearly shown in Figure 2, whereby an increased seating surface for the bar is provided.

The outer portion of the recess 19 is slightly wider than the bar 17 and to prevent movement of the bar within this portion of the recess, 50 radial flanges 21 are disposed one on each side of the recess 19, as is clearly shown in Figure 3. These flanges are preferably an integral part of the head, being bent at right angles to the surface of said head. It is also preferable to form 55

the bottom flange 20 by bending a portion of the head or plate as shown in the drawing. Manifestly the side flanges 21 take up the clearance between the sides of the bar 17 and the enlarged portion of the recess 19, whereby said side flanges snugly engage the sides of the bar. The flanges are metallic and have a certain amount of inherent resiliency and therefore act to frictionally hold the bar within the recess. In the event that the side flanges spread through use it is only necessary to bend them inwardly toward each other and obviously they will always snugly engage the sides of the bar 17.

An equal number of recesses is formed in each 15 of the heads 10 and 10' and when the heads are mounted on the shaft 13, said recesses are longitudinally alined with each other, whereby the longitudinal brush bars 17 may be inserted therein. The bars are of such length that their ends 20 terminate within the recesses of the end heads 10 (Figure 1). After the bars are in position within the recesses, arcuate retaining sheets 22 are secured by rivets, or otherwise, to the annular flanges 11 of the heads 10 and 10'. As is clearly 25 shown in Figure 2 one of the sheets is located between the brush bars 17, and each sheet extends substantially throughout the length of the cylinder. The width of each sheet is such that its longitudinal edges overlie the longitudinal edges 30 of the brush bars 17 on each side thereof and manifestly, the sheets prevent displacement of the bars from the recesses 19, whereby said bars are firmly held in place therein. The sheets not only serve to hold the bars in position but due to 35 their curvature form a substantially continuous surface, whereby cotton or other material cannot fall between the heads and bars when the cylinder is being used.

From the above, it will be seen that a very simple and sturdy structure is produced. The heads 40 may be easily stamped out which not only reduces the cost, but also assures all of the heads being of the same size. The flanges 20 at the base of the recesses 19 provide an amplified area 45 on which the brush bars rest, while the side flanges 21 firmly hold the bars against lateral displacement. The curved retaining sheets confine the bars within the recesses and form the surface of the cylinder, and removal of the sheets 50 allows the bars 17 to be readily removed for repair or replacement. The flanges 11 on the heads not only provide ready accessible means 55 for attaching the sheets but also add rigidity to the structure as they strengthen the heads.

55 What I claim and desire to secure by Letters Patent is:

1. A doffing cylinder for cotton machines including, end members each having recesses formed around its marginal portion, longitudinal brush bars extending between the members and mounted in corresponding recesses of the members, each member having a peripheral flange, and means engaging the brush bars and secured to the flanges of the members for retaining said 65 bars within said recesses.

2. A doffing cylinder for cotton machines including, end members each having recesses formed around its marginal portion, longitudinal brush bars extending between the members and mounted in corresponding recesses of the members, each member having a peripheral flange, and means overlying the longitudinal edge portions of the bars and secured to the flanges of the members for retaining said bars within said 70 recesses.

3. A doffing cylinder for cotton machines including, end members each having recesses formed around its marginal portion, longitudinal brush bars extending between the members and mounted in corresponding recesses of the members, and a plurality of curved retaining sheets located between the bars and secured to the members, each sheet having its longitudinal edge portions overlying the edge portions of the bars on each side thereof to retain said bars within 10 their recesses.

4. A doffing cylinder for cotton machines including, end members each having recesses formed around its marginal portion, longitudinal brush bars extending between the members and mounted in corresponding recesses of the members, and a plurality of curved retaining sheets located between the bars and secured to the members each sheet having its longitudinal edge portions overlying the edge portions of the bars 20 on each side thereof to retain said bars within their recesses, said sheets being substantially equal in length to the length of the bars whereby said sheets form the outer surface of the cylinder.

5. A doffing cylinder for cotton machines including, peripherally flanged end members each having recesses formed around its marginal portion, intermediate peripherally flanged supporting members located between the end members, each intermediate member having recesses around its 30 marginal portion, longitudinal brush bars mounted in corresponding recesses of the end and intermediate members, and means engaging the brush bars and secured to the peripheral flanges of both the end and intermediate members for retaining 35 the bars within the recesses.

6. A doffing cylinder for cotton machines including, flanged end members each having recesses formed around its marginal portion, intermediate flanged supporting members located between the end members, each intermediate member having recesses around its marginal portion, longitudinal brush bars mounted in corresponding recesses of the end and intermediate members, and a plurality of arcuate retaining sheets 45 located between the bars and secured to the flanges of the end and intermediate members, each sheet having its longitudinal edge portions overlying the edge portions of the bars on each side thereof for retaining said bars within the 50 recesses.

7. A doffing cylinder for cotton machines including, flanged end members each having recesses formed around its marginal portion, intermediate flanged supporting members located between the end members, each intermediate member having recesses around its marginal portion, longitudinal brush bars mounted in corresponding recesses of the end and intermediate members, and a plurality of arcuate retaining sheets 60 located between the bars and secured to the flanges of the end and intermediate members, each sheet having its longitudinal edge portions overlying the edge portions of the bars on each side thereof for retaining said bars within the 65 recesses, said sheets being sufficiently long to overlie both end members, whereby the sheets form a substantially continuous surface.

8. A doffing cylinder for cotton machines including, circular end members, each having a 70 plurality of recesses formed in its marginal portion, a laterally directed flange at the base of each recess, side flanges on each side of each recess, longitudinal brush bars insertable within the recesses, each bar resting against the 75

flange at the base of each recess and being engaged by the side flanges, and cylinder closure means extending between and engaging the outer surface of the brush bars and secured to the end members for retaining the bars within the recesses.

- 5 9. A doffing cylinder for cotton machines including, circular end members, each having a plurality of recesses formed in its marginal portion, a laterally directed flange at the base of each recess, side flanges on each side of each recess, longitudinal brush bars insertable within the recesses, each bar resting against the flange at the base of each recess and being engaged by the said flanges, and curved means overlying the uppermost longitudinal edge portions of the bars and secured to the members for retaining said bars within said recesses, whereby the curved means forms a substantially continuous surface.
- 10 10. A doffing cylinder for cotton machines including, circular end members, each having a plurality of recesses formed in its marginal portion, a laterally directed flange at the base of each recess, side flanges on each side of each recess, longitudinal brush bars insertable within the recesses, each bar resting against the flange at the base of each recess and being engaged by the side flanges, and a plurality of curved retaining sheets located between the bars and secured to the members each sheet having its longitudinal edge portions overlying the edge portions of the bars on each side thereof to retain said bars within their recesses, said sheets being substantially equal in length to the length of the bars whereby said sheets form the outer surface of the cylinder.
- 15 20 25

at the base of each recess and being engaged by the side flanges, and a plurality of curved retaining sheets located between the bars and secured to the members each sheet having its longitudinal edge portions overlying the edge portions of the bars on each side thereof to retain said bars within their recesses.

5 11. A doffing cylinder for cotton machines including, circular end members, each having a plurality of recesses formed in its marginal portion, a laterally directed flange at the base of each recess, side flanges on each side of each recess, longitudinal brush bars insertable within the recesses, each bar resting against the flange at the base of each recess and being engaged by the side flanges, and a plurality of curved retaining sheets located between the bars and secured to the members each sheet having its longitudinal edge portions overlying the edge portions of the bars on each side thereof to retain said bars within their recesses, said sheets being substantially equal in length to the length of the bars whereby said sheets form the outer surface of the cylinder.
